UNITED STATES PATENT OFFICE

THOMAS L. PARKER, OF CHICAGO, ILLINOIS, ASSIGNOR TO THE STANDARD ELECTRIC MANUFACTURING CO., OF CHICAGO, ILLINOIS, A CORPORATION OF ILLINOIS

MAIL BOX

Application filed September 17, 1927. Serial No. 220,163.

My invention belongs to that general class of devices known as mail boxes and relates more particularly to a box or receptacle for use in apparent buildings, hotels, offices, office buildings or wherever found applicable, the same being so constructed that the postman or carrier, by opening one door to which he alone has the key, can deposit the mail in anyone or all of a plurality of individual boxes, the addressee or recipient of the mail matter access only to his own box for which he alone has his individual key.

It has as an object the production of mail boxes of the kind described that are so constructed that it is impossible for others than the mail carrier to deposit anything in the boxes whereby peddlers and others are prevented from dropping circulars, samples or other matter in the box to the annoyance of the box holder and the inconvenience to the mail carrier.

The invention has among its further objects, the production of a mail box that is simple, compact, efficient, durable, attractive, inexpensive to manufacture and install and which will comply with post office regulations.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

40. Fig. 1 is a perspective view of an embodiment of the invention, the carrier's door being shown in two positions;

Fig. 2 is a sectional view taken substantially on line 2—2 of Fig. 1;

45. Fig. 3 is a sectional view taken substantially on line 3—3 of Fig. 1;

Fig. 4 is a sectional view taken substantially on line 4—4 of Fig. 1;

50. Fig. 5 is an enlarged view taken substantially on line 5—5 of Fig. 2;

Fig. 6 is an enlarged view taken substantially on line 6—6 of Fig. 2;

Fig. 7 is a rear view of a portion of the individual door showing the lock;

Fig. 8 is a sectional view through the 55 same taken substantially on line 8—8 of Fig. 1;

Fig. 9 is a face view of another embodiment of the invention;

Fig. 10 is a sectional view taken substantially on line 10—10 of Fig. 9; and

Fig. 11 is a sectional view taken substantially on line 11—11 of Fig. 9.

Referring to the drawings in which only two embodiments of the invention are shown, 65 1 represents a front panel plate to a container having the back 2, sides 3 and top and bottom 4 and 5, respectively. Arranged within the container are partitions 6 dividing the same into independent compartments or boxes. The size of the container as a whole depends upon the number of compartments desired and the desired size of the same. Generally, it is preferred to make the compartments of sufficient size to take in the general run of 75 mail matter such as postal cards, letters and magazines as well as packages of moderate size. In the embodiment of the invention shown in Figs. 1 to 8, there is provided the master or carrier's door 7 common to a plurality of compartments or boxes and an individual door 8 for each compartment.

In making up the receptacle, I prefer to make the same of sheet metal and the back 2 and sides 3 may be made of a single or integral sheet with the top 4 and bottom 5 attached thereto. When so constructed, the top and bottom are secured to the sides and backs by providing tongues on one part as for instance, tongues 9 on the sides projecting through slots in the top and bottom and thence riveted over so as to firmly secure the parts together. The top and bottom may be flanged over as indicated at 10 making the same ordinarily dust-proof and likewise 85 strengthening the structure. The partitions 6 may be secured in place by the tongues 11 engaging the top, bottom and back walls. The front panel 1 I prefer to flange over as indicated at 12 to provide a finish and also to 100

flange over about the opening as indicated at 13 so as to overlie the side walls 3, top 4 and bottom 5, the flange being secured thereto in any suitable manner. The receptacle may be 5 provided with openings 14 through which screws may be passed securing the receptacle in the wall opening to which the mail box is to be fitted into.

The door 7 is preferably provided with a 10 wing or flange 17 at each side or end so arranged as to fit more or less closely to the inner faces of the sides 3 as shown in Fig. 2. A rod 18 is secured at its ends to the receptacle, the door being turned over the same 15 as indicated at 19 so as to provide a hinge. I also prefer to reinforce and stiffen the top edge of the door with a rod 20', the top edge being turned over as indicated at 20 so as to retain the same in place, lengthwise movement of the rod 20' prevented by the wings 20 17. The opening movement of the door 7 is limited by a slot and pin connection with the walls 3. As most clearly shown in Figs. 1 and 4, the walls 3 are provided with a slot 21 and the wings 17 connected with the sides 3 by a rivet or screw 22 carried by the wing and passing through the slot 21. Obviously, slotting the wing and providing the pin or rivet in the side wall will accomplish the 25 same result. The partitions 6 are perforated to permit the rod 18 to pass through the same and are notched as shown at 24 so as to provide clearance for the rod and turned over end 20 at the top of the door.

Below the large door 7 the partitions 6 are 30 of a width to extend between the doors and are preferably flanged over as indicated at 25—26 so as to form a finish between the doors. In this connection, it may be mentioned that the width of the face flange 25 may be made as desired either with the flange 26 spaced from the wall 6 as shown in Fig. 3 or brought substantially close thereto so that 25 is merely a rounded edge, this being merely a matter of preference. The free edges of the doors 8 are preferably flanged as indicated at 27 while the opposite edge 30 of each is bent around the rod 29. The rods 29 form hinges for the doors 8. The 35 same may be anchored at the upper end by projecting the end 31 through the rod 19. The rod 19, in this case, being stationary, the turned over portion 19 of the door being slotted so as to clear the portion 31 of the rod 29. The lower end may be anchored in any suitable manner. The door 7 is provided with suitable locking means 32 of the desired type to which the mail carrier or postman carries the key. The individual doors 40 8 are provided with individual locks 32' each box holder having his individual key which will unlock his personal box only. As shown, in Fig. 8, the locks 32' may be secured to the doors by screws 33 having riveted heads 45 which pass through the flange 35 on the lock

mechanism, the parts being locked together by the nuts 34. If desired, each door 8 may be provided with a sight opening 36 so that it may be determined by the individual whether there is any mail in the box without 70 opening the same. Each door may be provided with a very narrow slot 37 through which calling cards may be inserted in the absence of the box holder but which will not permit placing of circulars and unauthorized 75 material in the box. Same may also have means as indicated at 38 for placing an identification card with the holder's name or apartment number. Generally, the upper part of the front plate is made of sufficient 80 width and is embossed or depressed to receive the usual push button or other devices commonly associated with mail boxes.

The embodiment of the invention shown 85 in Fig. 9 is more or less similar to that just described except that, in this instance, the upper door is made in a plurality of panels secured together to operate as a unit. Referring to Figs. 9 to 11, 41 represents the front plate, 42 the back of the receptacle, 43 the sides, 44 and 45 the top and bottom and 46 the partitions. In this instance, the partitions 46 are flanged from top to bottom at the opening to provide a finish between the doors 48 and the doors 52. The doors 48 are turned over the rod 49 similar to the door 7 over the rod 18 and the doors are connected at their upper ends by the rod 50. In other respects, the device corresponds more or less 95 to the structure previously described.

By constructing the device as shown and described, it is obvious that other than changes in the proportions, devices of two or more compartments may be made similar in construction. The work is all practically 105 stamping work but the parts are so rigid when assembling that the box may be made with a considerable number of units or compartments without sacrificing strength or rigidity. The device is rigidly installed, is 110 attractive in appearance, is economical to manufacture and convenient in use.

Having thus described my invention, it is 115 obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a device of the kind described and in combination, a receptacle provided with partitions dividing the same into a plurality of associated compartments, a master door common to a plurality of compartments and arranged to enclose the front thereof, said master door hinged on a horizontal axis and 125

of a size to cover approximately one-half of the front of the compartments, individual doors for said compartments arranged to cover the remainder of the compartments, 5 each of said individual doors hinged independently of the others on a vertical axis, and a hinge for each of said doors anchored by the hinge of said master door.

2. In a device of the kind described and 10 in combination, a receptacle provided with partitions dividing the same into a plurality of associated compartments, doors for said compartments arranged to enclose the front thereof, said partitions of a width from front 15 to back to project between said doors to flush with their exterior faces, and thence bent back about themselves whereby the same fill the spaces between adjacent doors.

3. A housing having a plurality of receptacles with one open end, a master door operable to close a portion of each of said receptacles, a pintle on which said master door is hingedly mounted, and a plurality of individual doors each closing the remaining 25 open portion of one of said receptacles, said individual doors being hingedly mounted on pintles extending transversely to and anchored at one end to said first mentioned pintle.

30 4. A housing having a plurality of receptacles with one open end, a master door operable to close a portion of each of said receptacles, a horizontally extending pintle on which said master door is hingedly mounted, 35 and a plurality of individual doors each closing the remaining portion of one of said receptacles said individual doors being hingedly mounted on vertical pintles having one end anchored to said horizontal pintle.

40 In testimony whereof, I have hereunto signed my name.

THOMAS L. PARKER.
